TOTE TRAY

Anson W. Voorhees, Jr., and Carl C. Cole, Tucson, Ariz.,
assignors to Pioneer Products, Inc., Tucson, Ariz., a cor-
poration of Arizona

Filed Aug. 9, 1965, Ser. No. 86,494

Term of patent 14 years

(Cl. D58—12)

FIG. 1 is a front elevational view of a tote tray showing our new design.

FIG. 2 is a side elevational view thereof.

FIGS. 3 and 4 are vertical sectional views taken, respectively, on the lines 3-3 and 4-4 of FIG. 1.

FIG. 5 is a fragmentary rear view as seen in the direction of the arrow 5 of FIG. 4.

FIG. 6 is a cross-sectional view as taken on the line 6-6 of FIG. 5.

We claim:

The ornamental design for a tote tray, substantially as shown.
